(57) **CLAIM**

The ornamental design for a game, as shown and described.

DESCRIPTION

FIG. 1 is a front isometric view of a game layout showing our new design.

FIG. 2 is a rear isometric view of a game layout showing our new design.

FIG. 3 is a front view of a game layout showing our new design.

FIG. 4 is a rear view of a game layout showing our new design.

FIG. 5 is a left side view of a game layout showing our new design.

FIG. 6 is a right side view of a game layout showing our new design; and,

FIG. 7 is a top plan view of a game layout showing our new design.

The claim is directed to the collective appearance of the game shown in the figures. The component of the set are

(Continued)

arranged on the drawing sheets for the convenience of illustration, and the relative position of the game forms no part of the claimed design.

1 Claim, 6 Drawing Sheets
